EXTENSION CURTAIN-ROD.

1,005,239.

Specification of Letters Patent. Patented Oct. 10, 1911.

Application filed December 21, 1909. Serial No. 534,282.

To all whom it may concern:

Be it known that I, CHRISTIAN F. LAUN, a citizen of the United States, and a resident of Waterville, in the county of New Haven and State of Connecticut, have made and invented certain new and useful Improvements in Extension Curtain-Rods, of which the following is a specification.

My invention relates to an improvement in extension curtain rods or poles, and more particularly to that kind or type thereof known as "goose neck", wherein the ends are curved or bent around at right angles to the remaining portions of the rod, the object of the invention being to so construct the rod and retaining brackets therefor, that all danger of them becoming disengaged when properly assembled, will be obviated.

A further object is to so construct and assemble the parts that the rods may be easily and readily engaged with or disengaged from the brackets.

A further object of the invention is to so construct the article that it will be cheap and economical to produce and strong and durable in use, and with these and other ends in view, consists in certain novel features of construction and combinations of parts, as will be hereinafter fully described.

80 and pointed out in the claims.

In the accompanying drawings, Figure 1 is a top plan view of a rod constructed in accordance with my invention and attached to a window or door frame. Fig. 2 is a sectional view of a bracket, the rod being omitted. Fig. 3 is a similar view showing the end of the rod assembled therewith. Fig. 4 is a detached view in perspective of the centering rivet. Fig. 5 is a view in perspective of one end of the rod. Fig. 6 is a view partly in section and partly in elevation of a modified form of the bracket, one end of the rod being shown in dotted lines and assembled therewith. Fig. 7 is a view in perspective of another modified form of the bracket, and Fig. 8 a view in perspective of a part of a bracket of still further modified form.

Referring to the drawings it will be seen that the invention has reference to extension rods made of tubular form, the one part 10 telescoping within the other part 11, each end being curved or bent around at right angles to the remaining portions of the rod.

To a wall, door frame, window frame, or other suitable support, are secured brackets for receiving and removably holding the ends of the rod 10, 11, these brackets consisting primarily of a support on which the ends of the rod rest and of a stop against which the extreme ends of the rod impinge, in order to prevent said rod from tilting or rocking, and to retain the same in its horizontal position.

In the preferred form, this bracket is constructed as illustrated in Figs. 1, 2 and 3, and comprises a plate 12 to which is secured the receptacle 18, this receptacle being provided at its forward ends with the spring fingers 14, 14, having the groove or recess 15 formed therein. At the rear end of this receptacle is formed a sleeve or tube 16 of a diameter to nicely contain the end of the curtain pole 10-11, and prevent the same from rocking or tilting downwardly when the parts are assembled as shown in Figs. 1 and 3. This receptacle 18 is secured to the plate 12 by means of the rivet 17, comprising the shank 18, flange 19, and head 20, the shank 18 passing through the plate 12 and upset or riveted on the rear side thereof within a recess 21 formed in said plate for that purpose, the flange 19 bearing against the rear plate or end of the receptacle and holding the latter tightly to said plate, the rounded head 20 being adapted to center the end of the rod when the parts are assembled, as hereinafter described. As the two brackets are identical in construction, the description of one suffices for the other.

90 Each end of the rod is preferably constructed as illustrated in Fig. 5, that is, is provided on its end with a ferrule or sleeve 21-22, provided with the rib 23 and with the indentation or recess 24 in its extreme end.

In assembling the rod with the brackets, each end is inserted in the receptacle 18; the extreme end thereof, that is, the ferrule 22, slips into the sleeve or tube 16, the rounded head 20 of the rivet 17 entering the recess 24 in the ferrule and acting to properly position or center the same. The rib 23 on the end of the rod is received into the groove or recess in the spring fingers 14, whereby through the medium of the spring fingers and the rib and groove formed on the end of the rod and in the spring fingers respec-

tively, the ends of the rods are securely held from accidental disengagement with the brackets.

I have found in practice that this construction is an extremely strong one, and withstands a much greater strain than is ever imposed upon it in practice; the parts are easily assembled, and by slightly lifting the rod upwardly and disengaging it from the spring fingers, it is easily and readily disengaged from the brackets. Instead, however, of employing the receptacle 18, constructed as above described, it may be constructed as illustrated in Figs. 6, 7 and 8.

In Fig. 6, the bracket is shown as comprising the plate 25 provided with a pin 26, the extreme end 27 of which is bent upwardly to enter the hole or opening 28 formed in the end 29 of the rod. In the plate 25 is also secured the stop 26, against which the rod 29 impinges when assembled, as illustrated in Fig. 6. Instead of employing a stop 26 in the form of a pin as above described, a portion of the plate may be struck outwardly, as illustrated in Fig. 7, wherein the plate 30 is slotted and the slotted portion stamped outwardly as illustrated at 31, against which latter the end of the pole will strike or impinge when the parts are properly assembled.

As illustrated in Fig. 8, the metal, instead of being slotted, may be punched or thrown outwardly, as illustrated at 32, such portion being integral with the plate 33, and forming a stop for the end of the pole when supported upon the pin 34.

In each and all of the above instances, it will be noted that the bracket consists of a plate for attachment to the window or door frame, a support upon which rests the end of the pole, and a stop against which the end of the pole or rod strikes or impinges when properly assembled with the bracket and when said rod extends outwardly in a horizontal plane from said brackets.

Having fully described my invention, what I claim as new and desire to secure by Letters Patent, is:

1. A curtain pole bracket comprising a plate adapted to be secured to a wall and to support the end of a rod extending at right angles to the wall, said plate having a support curved in cross-section adapted to extend along the under side only of the end of a rod and which support is provided with a groove adjacent its free end and extending in a plane at right angles to its length; the end of said support adjoining said plate being tubular in form and adapted to receive the extremity of a rod supported by said bracket and said tubular portion extending throughout a part only of the length of said support.

2. A curtain pole bracket comprising a plate adapted to be secured to a wall and to

support the end of a rod extending at right angles to the wall; said plate having a support adapted to extend along the under side only of the end of a rod, and said support having means for engaging a rod to prevent the same from moving away from said plate; said bracket having also a stop adapted to be engaged by the upper side only of the extremity of a rod whereby the same is prevented from tipping about the end of said support as a fulcrum.

3. The combination with a rod, the ends of which are bent so as to extend at right angles to its intermediate portion; of two brackets adapted to be secured to a wall and to support the ends of said rod, each bracket comprising a plate having a support extending along the under side only of the end of said rod, and which support is provided with means adjacent its end for engaging the rod to prevent the same from moving away from said plate; said bracket having also a stop adapted to be engaged by the upper side only of the extremity of the rod, whereby the same is prevented from tipping about the end of said support as a fulcrum.

4. The combination with a rod, the ends of which are bent so as to extend at right angles to its intermediate portion and which ends are provided each with a circumferentially extending rib; of two brackets adapted to be secured to a wall and to support the ends of said rod, each bracket comprising a plate having a support, curved in cross-section, extending along the under side only of the end of said rod, and which support is provided with a groove within which the rib aforesaid of said rod lies when the parts are assembled; the end of said support adjoining said plate being tubular in form, and the extremity of said rod extending into said tubular portion said tubular portion extending throughout a part only of the length of said support.

5. The combination with a rod, the ends of which are bent so as to extend at right angles to its intermediate portion and which ends are provided each with a circumferentially extending rib; of two brackets adapted to be secured to a wall and to support the ends of said rod, each bracket comprising a plate having a support extending along the under side only of the end of said rod and provided with spring fingers at its free end adapted to embrace said rod, and which spring fingers have a groove within which the rib aforesaid of said rod lies when the parts are assembled; the end of said support adjoining said plate being tubular in form and extending throughout a part of the length of said support, and the extremity of said rod extending into said tubular portion.

6. In an article of the character described, the combination with a telescopic rod, the

ends of which are bent at right angles thereto, each of said ends being provided with a rib and the extreme end with a recess, of brackets for supporting the ends of said rod, each of said brackets comprising a plate, a support having grooved spring fingers at its outer end and a tube at its inner end, and which tube extends throughout a part only of the length of said support and a rivet for securing said support and plate together and

adapted to fit within the recessed end of the rod, substantially as described.

Signed at Waterville, in the county of New Haven, and State of Connecticut, this 18th day of December, A. D. 1909.

CHRISTIAN F. LAUN.
